UNITED STATES PATENT OFFICE.

HARVEY HUBBELL, OF BRIDGEPORT, CONNECTICUT.

PULL-SOCKET.

1,229,464.

Specification of Letters Patent. Patented June 12, 1917.

Application filed November 29, 1916. Serial No. 134,211.

To all whom it may concern:

Be it known that I, HARVEY HUBBELL, a citizen of the United States, residing at Bridgeport, county of Fairfield, State of Connecticut, have invented an Improvement 5 in Pull-Sockets, of which the following is a specification.

This invention relates to the class of 10 sockets for incandescent electric lamps, illustrated and described in my former Letters Patent 565,541 dated Aug. 11, 1896, 693,799 dated Feb. 18, 1902, and 994,518 dated June 6, 1911, and has for its objects to generally improve the construction and mode of operation 15 of the socket switch, and more especially to increase the current-carrying capacity of the switch without increasing its size, or materially increasing the cost of production. This I accomplish by providing an 20 operating lever, by means of which the operating plate or wheel is actuated, and interposing a tension spring between the operating lever and the operating wheel which is additionally wound by forward movement 25 of the operating lever, and the effect of which is to cause the spring arms of the contact plate when they leave the shoulders at the ends of the inclines on the lower insulating block to jump forward as well as 30 inward, and thus produce a much quicker make and break than has been possible with any pull socket heretofore produced.

In the accompanying drawing forming a part of this specification,

35 Figure 1 is an elevation of my novel pull socket, full size;

Fig. 2 a section on the line 2—2 in Fig. 1, looking in the direction of the arrows;

40 Fig. 3 a plan view on an enlarged scale of the switch with the socket shell removed;

Fig. 4 an elevation corresponding with Fig. 3;

Fig. 5 a section on the line 5—5 in Fig. 4, looking in the direction of the arrows;

45 Fig. 6 a plan view of the lower insulating block, the standards being in section on the line 6—6 in Fig. 4, looking in the direction of the arrows;

Fig. 7 a detail elevation of the operating 50 lever and the operating plate, detached; and

Fig. 8 is a plan view of the contact plate, detached.

ing a loose connection with the operating plate. The operating lever is provided on its lower side with a hub 39 corresponding with the hub on the operating plate and the connection between said lever and plate is by means of a lug 40 lying between and co-operating with lugs 36 and 37 on the operating plate. The operating lever is provided on its upper side with a lug 41 which is engaged by a hook on the lower end of an operating spring 42, the other end of which engages a hole 43 in the head of the center post. The upper insulating block is provided in its under side with an angular recess 44 which is adapted to receive the angular head of the center post loosely and hold it against rotation.

45 denotes a tension spring normally under tension, which is coiled about hubs 35 and 39, the ends of which are connected respectively to the operating lever and to the operating plate, as clearly shown in Fig. 7, and the action of which is to normally hold lug 40, on the under side of the operating lever, in engagement with lug 36 on the operating plate and later to engage lug 37, as will be more fully explained.

In the present instance, I have shown the switch as operated by a cord 46 the inner end of which is secured in an insulating bushing 47 at the outer end of the operating lever.

For convenience in description I have called part 26 a center post although in the present instance it is placed eccentrically to the insulating blocks. It is wholly immaterial, however, so far as the present invention is concerned, whether the center post is placed concentrically with or eccentrically to the insulating blocks.

Standard 13 is provided with a binding screw 48, and standard 14 with a binding screw 49 to which conducting wires not shown are attached. The current passes from standard 13 to plate 19, to the contact plate, to plate 21 and through screw 24 to the center contact. Returning through the lamp, not shown, the current passes through screw shell 15 and through screw 16 to standard 14 and binding screw 49.

The operation is as follows: When the cord is pulled the operating lever will be moved forward. The tension spring is strong enough, however, to retain lug 40 upon the operating lever in engagement with lug 36 upon the operating plate during the first portion of the movement, the operating plate moving with the operating lever. As the spring arms of the contact plate ride up the inclines on the lower insulating block, however, the frictional engagement of the spring arms with the inclines will commence to retard the movement of the operating plate and lug 40 upon the operating lever 65 will pass out of engagement with lug 36

upon the operating plate and into engagement with lug 37 on said plate, by which engagement the operating plate will now be carried forward. The normal tension of the tension spring is increased by the winding it receives when lug 40 passes out of engagement with lug 36 and into engagement with lug 37, this being the position of the parts when the spring arms of the contact plate reach the shoulders at the ends of the inclines. When the spring arms leave the shoulders, the operating spring will act as in my said former patents to force the spring arms of the contact plate downward into engagement with either plates 19 and 21 or the insulating inclines. In my present structure, however, I have the additional effect of the tension spring in making a quick make or break of the circuit. When the spring arms pass off the shoulders, the tension spring will cause the operating plate, carrying with it the contact plate, to jump forward until lug 36 on the operating plate engages lug 40 on the operating lever, so that instead of simply dropping down into engagement with the inclines through the action of the operating spring, the spring arms, through the co-operation of the tension spring with the operating spring, will jump forward and engage the inclines at a slight distance forward from the shoulders at the bases of the inclines.

The result is, that no matter how slow the pull upon the cord may be, the instant the spring arms leave the shoulders they will be caused to jump forward through the action of the tension spring and the make or break will be much quicker than has heretofore been possible. The operating lever and the operating plate are returned to their normal position after each actuation by the operating spring as in my said patents referred to. When the spring arms of the contact plate are in engagement with plates 19 and 21 the circuit will be closed and actuation of the operating lever and operating wheel as already described, will carry the spring arms off from plates 19 and 21, said arms dropping over the abrupt shoulders and into engagement with the insulating inclines thus breaking the circuit simultaneously in two places.

The next actuation carries the spring arms off from the insulating inclines and into engagement with plates 19 and 21 thus closing the circuit again.

Having thus described my invention, I claim:

1. In a structure of the character described, in combination, a rotatable contact plate, an oscillatable operating plate by which the contact plate is actuated, an oscillatable operating lever having a loose connection with the operating plate by which the latter is actuated, and a tension spring, intermediate the operating lever and the op-

erating plate, the tension of which is increased by actuation of the operating lever.

2. In a structure of the character described, in combination, a block provided with inclines each terminating in an abrupt shoulder, a rotatable contact plate having spring arms adapted to engage said inclines, an oscillatable operating plate by which the contact plate is actuated, an oscillatable operating lever having a loose connection with the operating plate by which the latter is actuated, and a tension spring, intermediate the operating lever and the operating plate, the tension of which is increased by actuation of the operating lever, said spring causing the spring arms of the contact plate to jump forward when they pass off the shoulders.

3. In a structure of the character described, in combination, a rotatable contact plate, an oscillatable operating plate by which the contact plate is actuated, and which is provided with spaced apart lugs, an oscillatable operating lever having a lug adapted to coöperate with the lugs on the operating plate, and a tension spring connected to said lever and plate and normally under tension, the tension of said spring being increased by actuation of the operating lever, substantially as described, for the purpose specified.

4. In a structure of the character described, in combination, a block provided with inclines each terminating in an abrupt

shoulder, a rotatable contact plate having spring arms adapted to engage said inclines, an oscillatable operating plate by which the contact plate is actuated, an oscillatable operating lever having a loose connection with the operating plate by which the latter is actuated, an operating spring acting on the operating lever, and a tension spring connected to the operating lever and to the operating plate and normally under tension, the tension of which is increased by actuation of the operating lever, substantially as described, for the purpose specified.

5. In a structure of the character described, the combination, with a contact plate and an operating plate by which the contact plate is actuated, of an operating lever having a loose connection with the operating plate, an operating spring acting on the operating lever, and a tension spring intermediate the operating lever and the operating plate, the tension of which is increased by actuation of the operating lever.

6. In a structure of the character described, the combination, with a contact plate and an operating plate by which the contact plate is actuated, of an operating lever having a loose connection with the operating plate, and a tension spring intermediate the operating lever and the operating plate, the tension of which is increased by actuation of the operating lever.

In testimony whereof I affix my signature.
HARVEY HUBBELL.
